DESIGN FOR A WATCH CHARM OR SIMILAR ARTICLE OF JEWELRY

Max Wolfson, Pittsburgh, Pa.

Application February 6, 1942, Serial No. 105,680

Term of patent 3½ years

To all whom it may concern:

Be it known that I, Max Wolfson, a citizen of the United States and residing in Pittsburgh, in the county of Allegheny and State of Pennsylvania, have invented a new, original, and ornamental Design for a Watch Charm or Similar Article of Jewelry, of which the following is a specification, reference being had to the accompanying drawing, forming a part thereof, wherein:

Figure 1 is a front perspective view; and Figure 2 is a rear perspective view of a watch charm or similar article of jewelry embodying my new design.

I claim:

The ornamental design for a watch charm or similar article of jewelry, substantially as shown.

MAX WOLFSON.
